UNITED STATES PATENT OFFICE.

ALBERT E. MAYNARD, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

LENS-GRINDING MACHINE.

Application filed August 5, 1920. Serial No. 401,402.

To all whom it may concern:

Be it known that I, ALBERT E. MAYNARD, a citizen of the United States, residing at Southbridge, in the county of Worcester 5 and State of Massachusetts, have invented certain new and useful Improvements in Lens-Grinding Machines, of which the following is a specification.

This invention relates to improvements in 10 grinding machines and has particular reference to an improved construction of multiple lens grinding machine.

One of the principal objects of the present invention is the provision of a simple 15 and improved construction of multiple spindle lens grinding machine which will permit of an extremely compact arrangement of parts, requiring minimum bench space for the number of spindles being employed, which will permit of a single motor 20 and shaft being employed to operate the several spindles either individually or simultaneously, and which will facilitate ready adjustment of the several parts of the 25 machine as required.

Other objects and advantages of my improved construction should be readily apparent by reference to the following specification taken in connection with the accompanying drawings, and it will be understood that I may make any modifications 30 in the specific details of construction shown and described within the scope of the appended claims without departing from or 35 exceeding the spirit of my invention.

Figure I represents a front view partially in section of a machine embodying my improvements.

Figure II represents a fragmentary plan 40 view of the base portion and drive.

Figure III represents a detail rear view of the driving mechanism.

In the drawings, the numeral 1 designates the main tub portion or frame of my 45 machine having a plurality of webs 2 at the top forming pockets to receive the separable tub members 3 which are secured to the webs as by bolts 4 for retaining the parts in position. Each of these tubs as a 50 unit has journaled therein a vertical spindle 5 provided with the worm gear 6 meshing with the worm 7 on the shaft 8, which is further provided with a driven sprocket 9. This sprocket 9 is disposed near the

upper portion of the tub and has extending rearwardly therefrom through the slot 10 in the upper part of the tub the sprocket chain 11 which also passes over the drive sprocket 12 for applying power to the parts in the base of the machine. It will 55 be understood that the lower part of the tub 3 is filled with oil to minimize the noise and friction of the parts when in operation. Secured at the rear of the portion 1 as by the brackets 13 are bearings 60 14 for the driven shaft 15, which has loosely mounted thereon the sleeves 16 which are here shown as of four in number. Said sleeves bear preferably at one end the sprockets 12 and near the other end the 65 drive pulleys 17 connected as by the belts 18 with the upper spindles 19 of the machine to rotate the latter. They also preferably terminate in the toothed or other clutch face construction 20 adapted to engage 70 with the opposed clutch member 21 keyed on the shaft 15 and shiftable as by the clutch yoke 22 engaged in the groove 75 23 of the clutch member 21 and operated by the handle 24 on the front of the member 1, the handle thus extending through the member 1.

It will thus be seen that in operation when the members 20 and 21 are placed in interlocking engagement the sleeve 16 and 80 drive sprockets and pulleys carried thereby will be rotated to respectively drive the upper and lower spindles of the machine at the correct relative speeds, while by throwing out the clutch any one of the units may 85 be stopped while the other units of the machine continue to operate as before, thus providing an individual control for the several portions of the machine in addition to the ordinary control through stopping 90 of the shaft 15.

It is to be noted that the upper spindles 19 are carried in rotatable transversely slideable heads 25 mounted on the standards 26, while the size of the parts is such that the 100 standards are disposed immediately adjacent one to the other. In this construction it is desirable to employ screw feed mechanism, such as indicated at 27 for transversely shifting the slide varying the upper 105 head 25. On account of the close position of the standards, however, it is not convenient to have individual hand operated

mechanism for accomplishing this result, which is, therefore, attained through placing of the pinions 28 on the ends of the adjusting mechanism 27 and journaling in 5 the upright supports 26 the horizontal shaft or shafts 29 bearing the drive gear 30 at its inner end intermediate a pair of supports 25 and at its outer end being provided with an operating hand wheel 31 to rotate 10 the shaft 29. The shaft 29 may either of itself be longitudinally slidable as well as rotatable, in which event the pinion 30 will be directly secured thereto, or may be stationary, in which event the pinion 30 will 15 be provided with the shift collar portions 32 to facilitate selective meshing of the pinion 30 with the desired gear 28 so that upon rotation of the shaft 29 if the members 28 and 30 are in mesh the member 28 20 will be rotated to adjust the slide and thus the upper head in one direction or the other as may be desired. Securing the pinion 30 direct on the shaft as at the left of Figure I entails the limitation that the parts 25 can then only be selectively adjusted, while in the construction at the right where a pair of pinions are employed the several shafts if desired may be simultaneously adjusted. In either event, however, the heads may be 30 very simply and easily adjusted from the end of the bench and any desired number of units may be assembled and coupled with a single adjusting shaft of the type indicated at the right of Figure I without necessitating extra bench room being taken up by allowance of individual mechanisms and yet each individual head may be individually adjusted as desired from the end of the machine, or if preferred the entire set 35 or any selected group of the heads may be similarly simultaneously adjusted with respect to its own individual lower spindles and be shifted any desired amount.

I claim:

45 1. A lens grinding machine including a bed, a plurality of separate tub units secured in the bed, supports rising from the bed and provided with transversely adjustable heads, upper spindles carried by each of 50 the heads, a lower spindle in each tub for cooperation with its opposed upper spindle, and means for singly or simultaneously laterally adjusting the said upper spindles.

55 2. A machine of the character described comprising a base, a plurality of supports rising from the base and each provided with a guide channel, a head slidably mounted in each guide channel, a spindle rotatably carried by each head, screw feed means carried by the support and engaging the head for transversely shifting the head, said screw feed means including a pinion, a shaft carried by the supports bearing a pinion shiftable into and out of engagement with the 60 pinion on the screw feed means whereby

the screw feed means may be actuated through rotation of the shaft, and a second set of spindles associated with the base and arranged in opposed relation to the head spindles and adapted for cooperation there- 70 with.

3. A lens grinding machine including a bed, a plurality of separate tub units secured in the bed, supports rising from the bed and provided with transversely adjustable heads, spindles carried by each of the heads, a second set of spindles one in each tub for cooperation with its opposed head spindle, means for singly or simultaneously laterally adjusting the said head spindles, 80 and means for singly or simultaneously rotating said spindles.

4. In a machine of the character described, the combination with a base, of a main drive shaft carried by the base, a sleeve loosely mounted on the drive shaft and bearing a drive pulley and drive sprocket, clutch mechanism for operatively connecting the shaft and sleeve, a tub unit detachably mounted on the base and bearing a spindle 90 and driving means for said spindle, drive connections between the sprocket on the sleeve and the spindle drive mechanism for operating the latter, an upright on the base adjacent said tub, a grinding head carried by the upright and having a spindle for co-operation with the spindle of the tub, and additional driving connections between the pulley on the sleeve and said spindle for actuating the latter whereby the operation of both spindles is controlled by the clutch mechanism. 95

5. In a machine of the character described, the combination with a base, of a main drive shaft carried by the base, a sleeve loosely 105 mounted on the drive shaft and bearing a drive pulley and drive sprocket, clutch mechanism for operatively connecting the shaft and sleeve, a tub unit detachably mounted on the base and bearing a spindle 110 and driving means for said spindle, drive connections between the sprocket on the sleeve and the spindle drive mechanism for operating the latter, an upright on the base adjacent said tub, a grinding head carried by 115 the upright and having a spindle for co-operation with the spindle of the tub, additional driving connections between the pulley on the sleeve and said spindle for actuating the latter whereby the operation of both spindles is controlled by the clutch mechanism, the grinding head being mounted for transverse sliding movement on its upright, and means for transversely shifting the head. 120

6. In a machine of the character described, the combination with a base, of a main drive shaft carried by the base, a sleeve loosely mounted on the drive shaft and bearing a drive pulley and drive sprocket, clutch mechanism for operatively connecting the 125

shaft and sleeve, a tub unit detachably mounted on the base and bearing a spindle and driving means for said spindle, drive connections between the sprocket on the sleeve and the spindle drive mechanism for operating the latter, an upright on the base adjacent said tub, a grinding head carried by the upright and having a spindle for cooperation with the spindle of the tub, additional driving connections between the pulley on the sleeve and said spindle for actuating the latter whereby the operation of both spindles is controlled by the clutch mechanism, the base being provided with a plurality of tubs and uprights correspondingly constructed, and the several grinding heads being mounted on the uprights for transverse sliding movement, and means for separately or simultaneously sliding the several heads on their respective uprights. 15
In testimony whereof I have affixed my signature, in presence of two witnesses. 20
